UNITED STATES PATENT OFFICE.

CHARLES L. TURLEY, OF WOODLAWN, PENNSYLVANIA.

LOOPER FOR ROLLING MILLS.

Application filed April 27, 1923. Serial No. 634,977.

To all whom it may concern:

Be it known that I, CHARLES L. TURLEY, residing at Woodlawn, in the county of Beaver and State of Pennsylvania, a citizen 5 of the United States, have invented or discovered certain new and useful Improvements in Loopers for Rolling Mills, of which improvements the following is a specification.

10 My invention relates to improvements in a piece of apparatus commonly used in rolling mills and called a looper. I have developed the invention in application to a looper for a skelp mill, and in that application I shall describe it; but it will be understood that it is generally applicable in rolling-mills, where the benefit and advantage hereinafter to be explained may be realized.

15 In the accompanying drawings Fig. I is a view in plan from above of a looper embodying my invention, as I practice it in connection with and as part of a steel mill. Fig. II is a view of the same apparatus, 20 seen in side elevation but with the intermediate portion of the trough removed. Figs. III and IV are views to larger scale, showing the looper itself in vertical and transverse section, and its carrying and operating parts in end elevation. These two 25 figures illustrate the swinging feature which is of the essence of the looper of my invention; Fig. III shows the parts in position for conveying the advancing material from roll-pass to roll-pass, Fig. IV shows the parts 30 in the position they assume after an advancing length of material has been fed from roll-pass to roll-pass, a position allowing the release of the "loop," that is to say the 35 reach of travelling material which spans the gap between roll-pass and roll-pass.

In the rolling of skelp for pipe an initial bar, say 30 feet long (I give dimensions by way of example merely, not at all by way 40 of limitation) is in a suitable furnace heated and brought to welding condition and temperature. It then is rolled in continuous operation, and as it emerges from the last roll-pass it is sheared. From the initial 45 30-foot blank, 26 lengths of skelp may so be produced, each skelp length measuring 20 to 22 feet long.

50 As mills are commonly built and operated the multiplicity of roll-passes are commonly grouped into units, termed "roughing mill" and "finishing mill," and there may be fur-

ther unit grouping, as in the provision of an "intermediate mill."

In mills for continuous rolling, the relative speed between succeeding passes within the unit is susceptible to predetermination and adjustment, that the elongation of the material is without difficulty taken care of. But, as between the succeeding units, this matter of relative speed is not so easily 60 dealt with, and in practice it is generally necessary so to speed the rolls that as rolling progresses the reach of material between the ultimate roll pass of an earlier unit and the initial pass of a later unit shall lengthen, 65 that is to say develop into a "loop."

The "looper" is the conveyor which, placed between the last pass of an earlier unit and the first pass of a later unit, carries the material from pass to pass, and, having 70 done so, permits the development of and provides for the safe and proper disposal of the loop, and for the tail end of the 75 length of the piece of material, when at last it emerges from the ultimate pass of the earlier unit.

The looper commonly employed in strip mills is essentially a trough, extending between the roll passes, in which trough the advancing material is initially carried from 80 pass to pass. It is pivoted adjacent its posterior end (that is to say, adjacent the ultimate pass of the earlier mill unit), on a transverse axis, to swing vertically in a plane of swing coincident with the line of 85 direction of advance of the material being rolled. Initially, as mills ordinarily are built, it extends horizontally. When it has served its essential duty as a conveyor it 90 swings downward, allowing the developing loop to sag into a pit provided beneath, to allow the free descent both of looper and of the developing loop.

It will be remarked of such a looper—and the observations will gain point after 100 considering what is here to follow—that, necessarily long, its outer end swings on a long radius; that after it has served as a conveyor and receded, the developing loop drags over its surface; and that it cannot be 105 elevated again until after the end of the piece of material under treatment has advanced beyond its range of swing.

Turning now to the drawings, the ultimate pass of a roughing mill (a pass of 110 edging rolls) is indicated at 1, the initial pass of a finishing mill at 2. Between these

the looper is arranged. The direction in which material under treatment advances is indicated by the arrow α .

- Intermediate between the roughing and finishing mills extends the looper. It is, as has been intimated, essentially a trough, serving to convey the forward end of an advancing length of material as it advances from roll pass 1 and deliver it to roll pass 2.
- 10 A medial section of this trough is mounted to swing from one to the other of two alternate positions: the one shown in Figs. I and III, the other in Fig. IV. In the position shown in Figs. I and III the trough is continuous, and serves its primary function as conveyor and guide; in the position shown in Fig. IV the medial trough section is swung aside, leaving a gap, in which gap the loop may develop.
- 20 The movable trough section is preferably no more than a section of the whole length of the trough structure, and, as will be seen in Figs. III and IV, the section which is movable preferably includes no more than 25 the trough bottom and one side, the other side wall being stationary. The axis of swing is not as in earlier structures transverse of the line of advance of the material but is parallel to that line, the direction of 30 swing is not in line of the travel of the material, but transverse thereto.

Specifically, the trough 3 has a movable section 4. This section 4 does not extend the whole length of the trough but is an intermediate section; it includes only bottom and one side wall; the opposite side wall, to which the numeral 3 is immediately applied, is continuous throughout the length of the trough. The movable section is pivoted on an axis which extends along one side of and closely adjacent to the trough.

Compared with the usual pivoted-trough looper, it will be observed of this, it swings in an arc of short radius, and therefore requires a relatively small amount of power to swing it; and it swings wholly out of the way of the loop, so that while open it is not rubbed upon by the advancing material, but the loop hangs free in the pit. (To the pit 50 in Fig. II the reference numeral 5 is applied.)

The movable trough section is carried on a swinging beam 13, and the beam 13 is counterweighted, as indicated at 6, and the weight is such as to hold the trough section normally to the closed position shown in Fig. III, even when sustaining the weight of an advancing length of material. The trough section is swung to the open, material-releasing position indicated in Fig. IV by energizing of an electro-magnet 7. To the armature of the magnet a beam 12 is linked. The beam is fulcrumed in a stationary support. The otherwise free arm of 65 the beam is linked to a crank-arm 8 borne

by the shaft 9. This shaft 9 is the fulcrum of the counterweighted beam 13, which beam, as has been said, carries the trough section 4. When the electro-magnet is de-energized the trough section swings by gravity to the 70 closed position shown in Fig. III.

The floor of the closed trough is not continuous, but there is a gap δ , between the forward end of the movable trough section 4 and the adjacent stationary portion of the trough, nearer to roll-pass 2. Furthermore the floor of this stationary portion of the trough is shaped, as best seen in Fig. II. It is in the form of a downwardly turning plate 10.

As clearly shown in Figs. III and IV, the width of the trough is adjustable by varying the position of the channel bars 11 whose webs face the trough within.

As shown in the drawings these channel bars 11 are riveted to their supporting beams, and the adjustment alluded to is in this instance determined at the time of fabrication, by the particular placing of the rivet holes. It is manifest, however, that in this matter of the mounting of and of the relative positioning of the bars 11, the engineer may freely use his professional knowledge. Ordinarily in this art rigidity under 90 service conditions is a matter of first importance.

The operation will readily be understood. When the forward end of a length of material is advancing from roughing mill to finishing mill the looper is in the position shown in Figs. I and III; the trough is closed. The material accordingly runs forward through the trough and its forward end enters the roll pass 2. Then the electro-magnet 7 is energized. This might be effected automatically; as a matter of fact I accomplish it by a manually controlled switch. Immediately the movable trough section swings to the open position shown in Fig. IV. Then as in rolling the reach of 105 travelling material lengthens, the loop sinks gradually and freely into pit 5. It hangs as indicated by the dotted line c , Fig. II.

The fact will be perceived that when the loop c has so sunk in the pit, the movable trough section may by de-energizing the magnet be swung to closed position again.

As compared with the pivoted trough of the prior art, sufficiently described above, the trough of my invention, being counterweighted, and swinging on a short radius (18 inches, as compared with 6 feet), may be much more easily and more rapidly swung, and with less expenditure of power. It swings entirely out of the way, the loop of material hangs free in the pit. The wear of the strip dragging in the trough is reduced, the trough may be kept cooler, and with the bad effects of warping lessened. The opened trough may be closed again 120

while a substantial part of the piece already conveyed remains still on the intake side of roll pass 2. This can be done without danger from accidental catching of material between moving parts. The next succeeding piece of material may then be fed at a closer interval after its predecessor. This makes for increase in production.

Manifestly the looper is applicable not to skelp mills only, not merely to strip mills, but is of general applicability in rolling elongate material.

I claim as my invention:

1. In a looper for rolling mills and in combination with two roll-stands placed at an interval apart, a laterally swinging trough adapted alternately to support a length of material advancing between the roll stands and to allow such length of material engaged by the rolls of such stands to hang free therefrom.
2. In a looper for rolling mills and in combination with two roll-stands placed at an interval apart, a two-part trough open-

ing and closing in a direction transverse to the path of advance of material from one to the other of the said roll-stands, and adapted alternately to support material in its advance from one roll-stand to the other, and to allow a length of material when engaged by the rolls of the said roll-stands to descend and hang free from roll-stand to roll-stand, between the separated parts of the opened trough.

3. In a looper for a rolling mill a trough with a gap in its bottom extending above a loop-receiving space, the section of the trough adjacent the gap to rearward being pivoted for lateral swing, the section forward of the gap being curved in upwardly and rearwardly convex curvature.

In testimony whereof I have hereunto set my hand.

CHARLES L. TURLEY.
